UNITED STATES PATENT OFFICE.

ROY S. MARSH, OF CHICAGO, ILLINOIS, ASSIGNOR OF ONE-FOURTH TO CLARENCE S. MARSH, OF EVANSTON, ILLINOIS.

LOCK.

1,205,370.

Specification of Letters Patent. Patented Nov. 21, 1916.

Application filed July 23, 1914. Serial No. 852,544.

To all whom it may concern:

Be it known that I, Roy S. MARSH, a citizen of the United States, residing at Chicago, in the county of Cook and State of Illinois, have invented certain new and useful Improvements in Locks, of which the following is a specification.

The invention has for its object the provision of a lock mechanism which shall be in the highest degree proof against unauthorized manipulation and which shall at the same time possess great simplicity of mechanical construction contributing to low cost of production and non-liability to get out of order.

In order that the invention may be readily understood by those skilled in the art a preferred embodiment of the same is set forth in the accompanying drawings and in the description based thereon. As, however, the invention is susceptible of embodiment in other and varied constructional forms the drawing and description are to be taken in an illustrative and not in an unnecessarily limiting sense.

In the drawings—Figure 1 is a longitudinal section through a mortise lock taken on the line 1—1 of Fig. 3 and showing the parts in a locked position; Fig. 2 is a similar section showing the parts in an unlocked position; Fig. 3 is a transverse section taken on the line 3—3 of Fig. 1; Fig. 4 is a fragmentary section illustrating a coupling of the sectional knob spindle; and Fig. 5 is an enlarged detail view in perspective of the key guard.

As illustrated, the bolt is represented at 11 forwardly pressed by the spring 12 and having a projecting portion 13 which extends 40 into the plane of rotation of the key 14. Immediately to the rear of the projection 13 is a guard member in the form of a lever 15 pivoted at 16 in such position that its forward end presents an unyielding abutment to oppose the unlocking movement of the bolt. The projection 13 has an extension 17 illustrated as being offset laterally. An arm 18 is rigidly affixed to the barrel 19 carried by the knob spindle 20 and is adapted 50 upon the turning of the knob to bear with its lower end against the extension 17 in order to retract the bolt 11 against the tension of the spring 12. Obviously, however,

if the guard lever 15 occupies the position shown in Fig. 1 behind the projection 13, 55 the bolt cannot be retracted by means of the manipulation of the knob. In order to provide for the operation of the bolt by means of the knob, however, a flexible connection is provided between the barrel 20 and the 60 guard lever 15 by means of a metallic band 21 secured to the barrel at 22 and having in its lower end a slot 23 taking over a pin 24 carried by the lever.

As constructed it is apparent that when 65 the knob is manipulated so as to rotate the barrel 19 the lever 15 will be raised by means of the flexible connection 21 from behind the projection 13 and permit the arm 18 to push the projection to the left thus retracting the 70 bolt.

The knob spindle 19 comprises two sections 19 and 19^a, as shown in Fig. 4, the sections having fixed thereon barrels 20 and 20^a respectively, which barrels have alined communicating slots 24 and 25. A bar 26 is pivoted at 27 in the slot 25 and the free end of the arm extends into the slot 24. A spring 28 mounted within the slot 25 below the arm 26 tends to press the free end of the arm 80 outwardly and maintain the same free of the slot 24. An operating member 29 is disposed adjacent the bar 26 and has an arcuate face 30 corresponding in extent to at least the arc of rotation of the said bar as 85 the knob is turned. A pair of push rods 31, 32 are mounted with their heads 31^a and 32^a in such a position as to be accessible at the edge of the door. The rod 31 is attached to or formed integral with the operating 90 member 29 and the two rods are connected by a rocking arm 33 pivoted at 34 so that as one moves in one direction the other moves in the opposite direction whereby the operating member 29 may be advanced or 95 retracted in order to hold the bar 26 in the slot 24 to effect a coupling between the sections of the spindle or to permit its expulsion from the slot 24 by means of the spring 28 in order to uncouple the sections. A detent 35 is upwardly pressed by means of the spring 36 into one of two notches formed in the push rod 32, serving to hold the operating member 29 in either of the two positions for which it may be set. 100

From the above description it will be

- readily understood that in the position of the parts illustrated in Figs. 1 and 2 the spindle sections are disconnected and consequently the knob on the outer side of the door cannot be utilized to operate the bolt 11 for the reason that it is entirely disconnected from the barrel 19 to which the members 21 and 18 are connected. On the other hand, if the push button 31^a be pressed inwardly the operating member 29 will press the bar 26 inwardly so as to couple the two barrels 20 and 20^a and thus provide for the manipulation of the bolt from the outer door knob.
- 15 Provision is made for the manipulation of the lock by means of a proper key and safeguarded against the employment of the wrong key in the manner following: A guard-operating member in the form of a lever 37 is pivoted at 38 above the guard lever 15 and is connected thereto by means of a link 39 having a pivotal connection with the lever 37 at 40, while the opposite end of the link 39 is connected to a pin 41 in 20 the guard lever 15. On the opposite side of the keyhole is pivoted at 42 a second guard in the form of a lever 43 and below the same is pivoted at 44 a guard-operating lever 45, the two levers 43 and 45 being connected by 25 means of a link 46. The adjacent free ends of the guard-operating lever 37 and the guard lever 43 lie in the same plane which is included in the plane of rotation of the key 14 and specifically in the plane of rotation of one of its projecting wards 47, the 30 ends of the two levers correspond substantially to a radial line drawn from the axis of the key.
- When the key 14 is inserted within the 35 lock its ward 47 occupies the position shown in Fig. 1 beneath the free end of the guard-operating lever 37 and as the key is rotated in a clock-wise direction, as indicated by the arrow in said figure, it engages the lower edge of the lever 37 and lifts the same, thereby lowering the opposite end of said lever and by means of the link 39 lowering the rear end of the guard lever 15 thus lifting the front end of said guard lever from 40 its position behind the projection 18 so as to leave the bolt free to be retracted. As the rotation of the key is continued its ward 47 would strike against the free end of the guard lever 43 and its further movement 45 would be arrested, were it not that a ward 48 on the opposite side of the key simultaneously engages the free end of the guard-operating lever 45 and depresses the same transmitting the movement of said guard lever by means of the link 46 to the rear end of the guard 43 thus causing the forward end of the said guard lever to be lifted to the 50 position indicated in Fig. 2 and permitting the ward 47 of the key 14 to pass thereunder.

As the key turns farther its ward 48 strikes 65 the projection 13 and forces the bolt to the left against the tension of its spring 12, the key at that time assuming the position illustrated in Fig. 2. Upon the reverse movement of the key the bolt is released and again made subject to the spring 12 while the ward 47 passes from beneath the free end of the guard lever 43 and permits the said guard to drop. It is also free to immediately thereafter pass beneath the free end of 70 the guard-operating lever 37 which is held in its upright position by the projection 13 bearing upon the free end of the guard lever 15 until after the ward 47 of the key is entered below the end of the guard-operating 75 lever 37. When the key is turned to its former position, indicated in Fig. 1, the levers drop by gravity to their original position as shown in said figure and the bolt is held against retraction by the unyielding 80 guard lever 15.

The characteristic feature of the lock mechanism just described is that the guard-operating lever 45 must be actuated before the ward 47 can pass the end of the guard 90 lever 43 and the guard-operating lever 37 must be actuated before the bolt can be retracted. Consequently if a key were filed with a notch in its back so as to clear the end of the guard lever 43 the lock would still 95 not operate for the reason that when the notched key cleared the guard lever 43 it would also clear the guard-operating lever 37 which is in the same plane and thus would fail to actuate the guard-operating lever 37 100 and through it the guard lever 15 so as to lift the latter out of engagement behind the projection 18.

Further provision is made against unlawful manipulation of the lock by the provision of a guard plate 49 of arcuate form and disposed concentric to the axis of the key immediately within the lock case. This guard plate is provided with wards 50, 51 and 52 which correspond with similar wards 110 of the key so as to permit the initial rotation of the key only when the wards of the key and of the guard plate correspond. Carried by the guard plate 49 is a guard arm 53 having an arcuate portion 54 which is 115 disposed in the plane of rotation of the key concentric to the key axis. The key is likewise provided with an aperture 55 which is adapted to receive the end 56 of the guard arm 53 and guide the key thereon. It will 120 be noticed that the aperture 55 of the key is radially in line with the ward 48 and consequently it will not suffice to provide a key with a notch which will clear the end 56 of the ward arm, as in that case the ward 48 125 would have to be dispensed with and the guard-operating lever 45 would not be depressed as the key was rotated.

It will be observed that the attachment between the flexible member 21 and the guard lever 15 is by means of a pin and slot, thus allowing the guard member 15 to be 5 operated independently by the key and by the knob without interfering one with the other, this being due to the motion at the point of attachment, the pin 24 being allowed to play idly within the slot of the 10 member 21 when operated by the key.

It will thus be observed that a lock is provided in which operating members occupying the same plane are required to be respectively engaged and cleared by the same ward 15 of the key and in which it is rendered impossible to provide for the clearing of one of said members by the filing of a notch without at the same time destroying the ability of the key to engage the other of said 20 members; also that the employment of an arcuate guard arm adapted to engage within an aperture of the key, which cannot be substituted by a notch, renders impossible the filing of a key to fit the lock.

2 I claim:—

1. In a lock, the combination with a bolt having a portion thereof projecting into the plane of rotation of the key and adapted for operative engagement by the key ward, of 30 a guard member arranged to oppose the retraction of the bolt, a second guard member arranged to oppose the key ward, and a pair of guard-operating members arranged to be engaged and operated each by a key ward, 35 the second guard and the operating member for the first guard presenting to the same key ward one an unyielding shoulder and the other a surface yielding under the pressure of the ward.
- 40 2. In a lock, the combination with a bolt having a portion thereof projecting into the plane of rotation of the key and adapted for operative engagement by the key ward, of a pivoted guard member arranged to oppose 45 the retraction of the bolt, a second pivoted guard member arranged to oppose a key ward, and a pair of pivoted guard-operating members arranged to be engaged and operated each by a key ward, the second guard 50 and the operating member for the first guard being arranged in a common plane and presenting to the same key ward one an unyielding shoulder and the other a surface yielding under the pressure of the ward.
- 55 3. In a lock, the combination with a bolt having a portion thereof projecting into the plane of rotation of the key and adapted for operative engagement by the key ward, of a guard lever arranged to oppose the retraction 60 of the bolt, a second guard lever arranged to oppose a key ward, and a pair of guard-operating levers arranged to be engaged and operated each by a key ward, the second guard lever and the operating lever

for the first guard being arranged in a common plane and presenting to the same key ward one an unyielding shoulder and the other a surface yielding under the pressure of the ward.

4. In a lock, the combination with a bolt 70 having a portion thereof projecting into the plane of rotation of the key and adapted for operative engagement by the key ward, of a guard lever arranged with its end behind the bolt projection, a second guard lever 75 arranged in the path of a key ward, an operating lever for the first guard, a link connection between one arm of the guard operating lever and the arm of the first guard lever, the free arm of the guard-operating lever being disposed in the same plane and adjacent to the end of the second guard lever in the path of the said key ward, a second guard-operating lever, a link connection between the second guard-operating 80 lever and the second guard lever, the free end of the second guard-operating lever disposed in the same plane as the first mentioned key ward and in the path of the ward 85 on the opposite side of the key, the first-mentioned ward acting through the first guard-operating lever to move the first guard lever out of the path of the bolt and the second guard-operating lever acting to move the second guard lever out of the path of the 90 first mentioned guard.

5. In a lock, the combination with a bolt having a portion thereof projecting into the plane of rotation of the key and adapted for operative engagement by the key ward, 100 of a guard arm disposed within the plane of rotation of the key, the key having a hole to receive the guard arm and to guide the key thereon.

6. In a lock, the combination with a bolt 105 having a portion thereof projecting into the plane of rotation of the key and adapted for operative engagement by the key ward, of an arcuate guard arm disposed within the plane of rotation of the key and concentric 110 to the key axis, the key having a hole to receive the guard arm and to guide the key thereon and provided on its edge opposite the aperture with a guard-operating surface.

7. In a lock, the combination with a bolt having a portion thereof projecting into the plane of rotation of the key and adapted for operative engagement by the key ward, of a key-receiving guard plate having wards 120 corresponding to the wards of the key, and an inwardly extending guard arm carried by the plate and having a portion extending into the plane of rotation of the key, the key having an aperture to receive the guard 125 arm and to guide the key thereon.

8. In a lock, the combination with a bolt having a portion thereof projecting into

the plane of rotation of the key and adapted for operative engagement by the key ward, of an arcuate key receiving guard plate having wards corresponding to the wards of the key, and an inwardly extending guard arm carried by the plate and having an arcuate portion disposed concentric to the key axis

within the plane of rotation of the key, the key having an aperture to receive the guard arm and to guide the key thereon.
